Application filed January 13, 1888.

STATEMENT.

To all whom it may concern:

Be it known that we, MARSHALL, KENNEDY & Co., (Limited,) a limited copartnership, duly formed, existing, and doing business under the 5 limited-partnership act of the legislature of Pennsylvania, and of which A. M. MARSHALL is chairman, W. M. KENNEDY vice-chairman, and F. J. WEIXEL, secretary and treasurer, all of whom are citizens of the United States, residing and domiciled in the county of Allegheny, State of Pennsylvania, and doing business at the corner of Liberty and Fifteenth streets, in the city of Pittsburg, in said county and State, have adopted a Trade-Mark for 15 Flour, of which the following is a clear, full, and exact description.

Our trade-mark consists of the representation or print of two stars, one above the other, and usually printed in red ink, around, over, 20 and across which are the words "Pearl Steam Mills, Double Extra Family Flour, Manufactured Expressly for Family Use by Marshall, Kennedy & Co., Limited, Pittsburgh, Pa.," all of which is surrounded by a double scalloped border and printed or stenciled upon one side 25 of flour-sacks.

This trade-mark has generally been arranged substantially as described; but other forms of words and arrangement thereof, color, and size of cuts and letters may be employed 3 without materially altering the character of our trade-mark, the essential feature of which is the representation of two stars, one above the other, as shown by the fac-simile.

This trade-mark has been used continuously 3 in business by us and our assignors since 1853 and by us exclusively since 1871.

The class of merchandise to which this trade-mark is appropriated is flour, and the particular description of goods comprised in said 4 class upon which it is used by us is flour.

It has been our practice to mark our trade-mark upon sacks of flour manufactured by us, and in manner substantially as shown by the fac-simile.
